[57] CLAIM

The ornamental design for a heat gun, as shown and described.

DESCRIPTION

FIG. 1 is a side elevational view of a heat gun, showing my new design;

FIG. 2 is an isometric view showing the front, top and left side thereof;

FIG. 3 is a top plan view thereof;

FIG. 4 is a bottom plan view thereof;

FIG. 5 is a front elevational view thereof;

FIG. 6 is a rear elevational view thereof;

FIG. 7 is a side elevational view of a second embodiment of a heat gun;

FIG. 8 is an isometric view showing the front, top, and left side thereof;

FIG. 9 is a top plan view thereof;

FIG. 10 is a bottom plan view thereof;

FIG. 11 is a front elevational view thereof; and

FIG. 12 is a rear elevational view thereof.

FIG. 1.

FIG. 2.

FIG. 3.

FIG. 4.

FIG. 5.

FIG. 6.

FIG. 7.

FIG. 8.

FIG. 9.

FIG. 10.

FIG. 11.

FIG. 12.
